UNITED STATES PATENT OFFICE.

CHARLES R. HOLDEN, OF CHICAGO, ILLINOIS.

RAILWAY-ROAD-BED CONSTRUCTION.

933,073.

Specification of Letters Patent.

Patented Sept. 7, 1909.

Application filed March 28, 1908, Serial No. 423,855. Renewed January 30, 1909. Serial No. 475,217.

To all whom it may concern:

Be it known that I, CHARLES R. HOLDEN, a citizen of the United States, residing at Chicago, in the county of Cook and State of Illinois, have invented a new and useful Railway-Road-Bed Construction, of which the following is a specification.

My invention relates, more particularly, to improvements in means for securing railway-rails in place on ties provided to receive them; and my object, generally stated, is to provide new and improved means for the purpose stated to the end of improving railway road-bed constructions.

Referring to the accompanying drawings—Figure 1 is a view in side elevation of a tie showing rails in cross-section secured thereto in accordance with my invention. Fig. 2 is a plan view of the construction illustrated in Fig. 1. Fig. 3 is a view of the parts comprising the means for binding the rails to the tie, the parts being shown in disassembled relation. Fig. 4 is a view in side elevation of an end of the tie illustrated in Fig. 1. Fig. 5 is a cross sectional view of another form of tie in connection with which my invention may be employed; and Fig. 6, a view in side elevation of a portion of the tie illustrated in Fig. 5.

The tie illustrated in Figs. 1 and 2 is of the U-shape type affording two upright flanges, or webs, 7. Each flange, near the opposite ends of the tie, carries two shoulders, each undercut, as represented at 9, to afford abutments for the outer flanges 10 of rails 11 seated on the top-surfaces of the webs 7. Projecting above the rail-seats at a sufficient distance from the abutments 8 to permit the rails to be applied to the ties and inserted into engagement with the undercut portions of the abutments, are ears 12 each of which contains a slot 13, preferably of arc-shape, affording a curved wall 14, each of these slots opening toward its coöperating abutments 8.

The means for fastening the rails in place on the tie each comprises a key 15 of arc-shape in cross-section corresponding with the arc described by the slots 13, the key having a shouldered rail-flange-engaging portion 16 which, when the key is inserted crosswise of the tie through the slots 13 in the opposed webs 7, as illustrated in Fig. 2, is caused to bear against the inner flange 17 of the adjacent rail and force the latter against the coöperating abutment 8.

As most clearly illustrated in Fig. 3 the portion of the key which engages with the bottom portions of the slots is provided with inclined surfaces 18 and 19, forming wedging surfaces, arranged in stepped relation, the depth of the companion slots 13 into which the key is insertable varying, as clearly illustrated at 20 and 21, in Fig. 4, whereby, when the key is inserted into the companion slots 13 the wedging surfaces 18 and 19 will simultaneously engage with the bottom portions of these slots.

To clamp a rail in place on the tie it is applied to its seat on the flanges and moved into engagement with the undercut portions 9 of the shoulders 8. The key is then inserted into the companion slots 13 and its inclined surfaces 18 and 19 are caused to ride upon the bottom portions of the slots 13 with the result of causing the key to be turned in the slots in a direction toward the rail, and thereby causing its rail-flange-engaging portion 16 to be forced down and against the inner flange 17 of the rail and securely clamp the latter to the tie. By forming the seats 13 in the flanges 7, as illustrated, the portion 16 of the key moves toward the rail and down against it, and therefore, as the stress exerted against the key is communicated to the curved wall 14 and bottoms of the slots 13, the resistance afforded by the rail-fastening means against displacement is great.

The key may be driven into the desired position for clamping the rail to the tie by striking it at its enlarged end with a sledge, or the like, or by means of the bolt-device illustrated of which the following is a description: The ears 12 are provided with bolt-holes 22 below the slots 13, and extending crosswise of the tie, one at each end thereof, is a bolt 23 which fits at its head 24 against the outer face of the tie-flange 7 containing the shallower of the slots 13. Each bolt projects at its opposite threaded end 25 beyond the larger end of the key with which it coöperates, and receives a washer 26 having an arc-shaped shoulder 27 which fits against the large end of the key, and is caused to bear forcibly against the latter by the screwing of a nut 28 on the bolt 23. Thus as the nut is turned the key is forced into close engagement with the rail. In addition to the means described for holding the key in place I may provide a wedge-shaped pin 29 which may be driven through

a slot 30 in the key and in engagement with the outer face of the adjacent tie-flange 7 to perform its function in a well-known manner.

5 The construction of tie illustrated at 31 in Figs. 5 and 6, is of the well-known I-beam type with angle-plates 32 riveted to it on opposite sides a longitudinal distance apart corresponding approximately to the gage 10 of the track desired. Each pair of plates is formed with the undercut shoulders 8 and slotted ears 12 as described of the flanges 7 of the preceding figures, this construction being designed for use with a key of the 15 form hereinbefore described. Thus it will be seen that the only difference between the construction illustrated in Figs. 5 and 6 and that of Figs. 1 to 4 inclusive, is that instead of making the shoulders 8 and ears 12 a part 20 of the rail-flange proper as described of the U-shaped tie construction, they are formed on separate plates bolted to the tie-proper.

A great advantage afforded by the construction of key described is that of the 25 adaptability of the key to be sprung into close engagement with the rail even though the parts of the construction may not be formed in exactly the proper proportions as is very liable to occur in practice.

30 What I claim as new, and desire to secure by Letters Patent, is—

1. The combination of a support for a rail containing a recess having a curved wall, an abutment for one of the lateral flanges 35 of the rail, a key provided with a rail-flange-engaging portion and insertible into said recess, and means for moving the key in said recess against its curved wall thereby causing the key to turn in the recess and bear at 40 its rail-flange-engaging portion against the other flange of the rail, for the purpose set forth.

2. The combination of a support for a rail containing a recess having a curved wall, 45 an abutment for one of the lateral flanges of the rail, a key provided with a rail-flange-engaging portion and insertible into said recess, and wedging means for moving the key in said recess against its curved wall 50 thereby causing the key to turn in the recess and bear at its rail-flange-engaging portion against the other flange of the rail, for the purpose set forth.

3. The combination of a support for a 55 rail containing a recess having a curved wall, an abutment for one of the lateral flanges of the rail, a key provided with a rail-flange-engaging portion and insertible into said recess, and wedge-surfaces carried by the 60 key and engaging with said support for causing the key to be moved in the recess against its curved wall thereby causing the key to turn and bear at its rail-flange-engaging portion against the other flange of the 65 rail, for the purpose set forth.

4. The combination of a support for a rail containing a recess having a curved wall, an abutment for one of the lateral flanges of the rail, and a key provided with a rail-flange-engaging portion and wedge-surfaces 70 on its bottom-portion and insertible into said recess, whereby the key is caused to be moved against said curved surface and be turned in the recess and bear at its rail-flange-engaging portion against the other 75 flange of the rail upon the act of inserting the key in the recess.

5. The combination of a support for a rail containing an arc-shaped recess, an abutment for one of the lateral flanges of the 80 rail, a key of arc-shape in cross-section provided with a rail-flange-engaging portion and insertible into said recess, and means for moving the key in said recess against the curved wall of the latter thereby causing the key to be turned therein and bear at its rail-flange-engaging portion against the other flange of the rail, for the purpose 85 set forth.

6. The combination of a support for a rail 90 containing an arc-shaped recess, an abutment for one of the lateral flanges of the rail, and a key of arc-shape in cross-section provided with a rail-flange-engaging portion and with a wedging surface on its lower edge 95 insertible into said recess transversely of the support, whereby the wedging-surface of the key is caused to bear against the bottom of the recess and turn the key at its rail-flange-engaging portion against the other 100 flange of the rail, for the purpose set forth.

7. The combination of a support for a rail having a plurality of upright webs, each containing a recess having a curved wall, 105 an abutment on the support for one of the lateral flanges of the rail, and a key provided with a rail-flange-engaging portion and wedging surfaces arranged in stepped relation, insertible into said recesses transversely of the support, whereby the key is 110 caused to be turned in the recesses against the curved walls thereof and bear at its rail-flange-engaging portion against the other flange of the rail upon the act of inserting the key in the recesses. 115

8. The combination of a support for a rail having a plurality of upright webs each containing a recess having a curved wall, 120 abutments on the support for one of the lateral flanges of the rail, a key provided with a rail-flange-engaging portion and insertible into said recesses, means for turning the key in said recesses to cause it to move against said curved walls and bear at its rail-flange-engaging portion against the 125 other flange of the rail, and means on the support operating against the key for holding the latter in adjusted position on the support.

9. The combination of a support for a rail 130

having a plurality of upright webs each containing a recess having a curved wall, abutments on the support for one of the lateral flanges of the rail, a key provided with a rail-flange-engaging portion and insertible into said recesses, means for turning the key in said recesses to cause it to move against said curved walls and bear at its rail-flange-engaging portion against the other flange of the rail, a bolt extending at its threaded end through one of said webs against which

it bears at its head, means movable on the bolt for engaging with the key, and a nut on the bolt for moving said last-named means toward the head of the bolt while 15 in engagement with the key, for the purpose set forth.

CHARLES R. HOLDEN.

In presence of—

R. A. SCHAEFER,
W. T. JONES.
